(57) **CLAIM**

The ornamental design for a model railroad rail, as shown and described.

DESCRIPTION

FIG. 1 is an isometric view of the model railroad rail;
FIG. 2 is a first end view of the model railroad rail;
FIG. 3 is a second end view of the model railroad rail;
FIG. 4 is top view of the model railroad rail;
FIG. 5 is a first side view of the model railroad rail;
FIG. 6 is a second side view of the model railroad rail; and,
FIG. 7 is a bottom view of the model railroad rail.
The broken lines in the drawings show the model railroad rail
that forms no part of the claimed design.
